Attorney

United States Patent Office.

A. H. CLARK, OF FOND DU LAC, WISCONSIN.

Letters Patent No. 66,677, dated July 16, 1867.

IMPROVED CAR-COUPLING.

The Schedule referred to in these Letters Patent and making part of the same.

TO ALL WHOM IT MAY CONCERN:

Be it known that I, A. H. CLARK, of Fond du Lac, in the county of Fond du Lac, and State of Wisconsin, have invented a new and improved Self-Acting Car-Coupler; and I do hereby declare that the following is a full, clear, and exact description thereof, which will enable others skilled in the art to make and use the same, reference being had to the accompanying drawings forming a part of this specification, in which—

Figure 1 is a longitudinal section of two railroad car draw-heads in position for connection with the car-couplers of my invention, taken in the line $x x$, fig. 2.

Figure 2 is a top view of a single draw-head with my car-coupler attached.

Figure 3 is a front view of my car-coupler detached.

Figure 4 is a side view detached.

Similar letters of reference indicate like parts.

This invention relates to a self-acting device for coupling railroad cars, which is very simple, strong, and sure in its operation.

A A represent ordinary iron belt-mouthed car draw-heads or bunters, each of which has a square cavity opening into it from the upper side for receiving a nicely fitted sliding iron block, *a*, on the under side of which is pivoted a solid hinge-flap, *b*, made to hang flush with the front side of the block *a* when open, and to double up against its bottom when pressed back by the shackle or link *c*, as shown at fig. 1. In the front side of the block *a* is a vertical groove for receiving a coupling-pin, *d*, the lower end of which rests upon the top of the hinge-flap *b* when the flap hangs down, as shown at figs. 3 and 4, and the upper end of which is attached by a link to a chain, *e*, which is connected with the block *a* for lifting it as required, for coupling and uncoupling. The chain *e* is designed to be used on freight cars for uncoupling them from the top. Long and narrow vertical recesses *f* are cut in the opposite sides of the block *a*, as seen in fig. 4, and set-screws *g g* pass through the opposite sides of the draw-head *A*, the ends of which screws project into these recesses and prevent the block from coming out of the draw-head, while at the same time it can slide up and down freely. A hole, *h*, is made in the draw-head to receive the end of the coupling-pin *d* when it drops in place to hold the link *c*, as shown in fig. 1.

For coupling cars the device is set by introducing the link *c* behind the coupling-pin *d* in the draw-head, when the hinge-flap *b* will be pushed back and rest upon the rear end of the link, and the weight of the block *a* bearing upon it will hold the link level, as shown at fig. 1, while in the opposite draw-head the device will be set by allowing the hinge-flap *b* to hang down straight and rest upon the opening or mouth of the draw-head; the coupling-pin *d* will then be held up by the flap. When in this position the draw-heads are brought together, the free end of the link *c* will be pushed against the hinge-flap *b*, and force it back so that the pin *d* will fall of itself and catch in the link, and thus by automatic action will complete the coupling of the cars to which the draw-heads are attached.

Having thus described my invention, what I claim as new, and desire to secure by Letters Patent, is—

The combination of the sliding-block *a*, the hinge-flap *b*, and the coupling-pin *d* with a draw-head on a railroad car, constructed and operating substantially as and for the purposes herein described.

A. H. CLARK.
